DESIGN FOR A SHOE

Robert Stewart Kilborne, Jr., Chappaqua, N. Y.

Application April 4, 1935, Serial No. 56,207

Term of patent 14 years

To all whom it may concern:

Be it known that I, Robert Stewart Kilborne, Jr., a citizen of the United States, residing in Chappaqua, county of Westchester, State of New York, have invented a new, original, and ornamental Design for a Shoe, of which the following is a specification, reference being had to the accompanying drawing, forming part thereof.

In the accompanying drawing,

I claim:

The ornamental design for a shoe, substantially as shown.
